(57) **CLAIM**

The ornamental design for a cutting tool guard for a table saw, as shown and described.

DESCRIPTION

FIG. 1 is a front elevational view of a cutting tool guard for a table saw showing our new design.

FIG. 2 is a right side elevational of the cutting tool guard.

FIG. 3 is a rear elevational of the cutting tool guard.

FIG. 4 is a left side elevational of the cutting tool guard.

FIG. 5 is a front perspective view from the left side of the cutting tool guard.

FIG. 6 is a rear perspective view from the right side of the cutting tool guard; and,

FIG. 7 is a top plan view of the cutting tool guard.

In the above drawing, any broken line illustration is not part of the design sought to be patented. In addition, any views not shown thereof do not form a part of the invention.
